INVENTOR—

FREDRICH J. KOBUSCH.
BY *Nigdon & Tongue.*
ATTY'S.

UNITED STATES PATENT OFFICE.

FREDRICH J. KOBUSCH, OF ST. LOUIS, MISSOURI.

HEATING-DRUM.

No. 836,447.

Specification of Letters Patent.

Patented Nov. 20, 1906.

Application filed January 4, 1906. Serial No. 294,520.

To all whom it may concern:

Be it known that I, FREDRICH J. KOBUSCH, a citizen of the United States, and a resident of St. Louis, Missouri, have invented certain new and useful Improvements in Heating-Drums, of which the following is a specification containing a full, clear, and exact description, reference being had to the accompanying drawings, forming a part hereof.

My invention relates to a heating-drum, and is an improvement on the heating-drum, patented by me November 14, 1905, No. 804,735.

The object of my invention is to generally improve the construction shown in the patent above referred to and particularly to construct a heating-drum that may be readily put together without the use of rivets or similar fastening devices.

A further object of my invention is to construct a simple heating-drum that will very effectually radiate the heat from the smoke and products of combustion that pass through the drum.

To the above purposes my invention consists of certain novel features of construction and arrangement of parts, which will be hereinafter more fully set forth, pointed out in my claims, and illustrated in the accompanying drawings, in which—

Figure 1 is a vertical section of a heating-drum constructed in accordance with my invention. Fig. 2 is a perspective view of the baffle-plates and framework that are located on the interior of the drum. Fig. 3 is a side elevation of one of the legs or frames that support the baffle-plates within the drum. Fig. 4 is a transverse section taken on the line 4 4 of Fig. 1.

Referring by numerals to the accompanying drawings, 1 indicates a cylindrical drum constructed of sheet metal and connected to the members of a vertical line 2 of stovepipe provided with the flaring ends 3. Horizontally disposed within the lower end of the drum 1 is a small sheet-metal cone 4, the apex of which points upwardly, and formed through said cone are the slots 5. Located a short distance above the cone 4 is a conical ring 6, of sheet metal, the diameter of which is slightly larger than is the diameter of the small cone 4. Formed through this ring 6 at suitable distances apart are slots 7.

Horizontally disposed in the upper end of the drum 1 is a low sheet-metal cone 8, provided with suitably-arranged slots 9, and the

diameter of this upper cone is somewhat larger than is the diameter of the ring 6.

A series of vertically-arranged frames 10 are removably arranged on the interior of the drum 1 and support the two cones and the ring in proper position therein. Each frame is constructed of a thin strip of sheet metal, the lower end of which is formed into a hook 11 and which engages in one of the slots 5 in the lower cone 4. From the edge of said lower cone 4 all of the narrow strips extend outwardly and downwardly to the lower end of the cylinder 1, and from this point they extend upwardly to a point approximately half-way between the ends of the cylinder 1. At this point the strips are doubled, as indicated by 12, and said doubled portions are extended upwardly and inwardly, and the ends of said doubled portions are formed into hooks 13, that engage through the slots 7 in the ring 6. The upper portions of the narrow strips forming the frames 10 extend upwardly from the doubled portions 12 to the top of the cylinder 1, and from thence said upper portions are bent downwardly and thence inwardly and upwardly beneath the edge of the upper cone 8, and the ends of said strips are formed into hooks 14, which engage through the slots 9 in the upper cone. There are preferably three of these frames, and as they are constructed of thin sheet metal they are readily bent into proper shape, so as to rigidly hold the two cones and the ring in proper position. Thus said cones and ring, together with the frames, are fixed together without the use of rivets or similar fastening devices, and the entire frame is removably positioned in the drum or cylinder 1.

95 The cones 4 and 8 act as baffle-plates for the smoke and products of combustion that pass through the drum, and the ring 6 tends to deflect the smoke and products of combustion to the center of the drum beneath the cone 8, and thus the smoke and products of combustion are retarded in their passage through the drum, and for this reason the heat from said smoke and products of combustion is radiated from the drum. The soot 100 passing upwardly through the stovepipe and drum will to a large extent be caught by the cones and ring and will be deflected thereby downwardly through the drum and lower portion of the stovepipe back into the stove 105 and there be consumed.

A heating-drum of my improved construc-

tion is simple, strong, and durable, can be very cheaply manufactured, owing to its simple construction, and the frames and cones can be manufactured and shipped in knockdown form and readily put together without the use of rivets or similar fastening devices.

I claim—

1. The combination with a cylinder, of a series of vertically-arranged frames detachably held within the cylinder, hooks formed integral with said frames, a pair of cones secured to the hooks at the upper and lower ends of the frames, and a conical ring arranged between the cones and secured to the hooks at the centers of the frames; substantially as specified.

2. An improved heating-drum, constructed with a cylinder, a series of frames vertically disposed within the cylinder, a large cone within and near the upper end of the cylinder

and secured to the upper ends of the frames, a small cone in and near the lower end of the cylinder and supported by the lower ends of the frames, and a conical ring arranged between the cones and supported by the central portions of the frames; substantially as specified.

3. In a heating-drum, a cylinder, a large imperforate cone concentrically supported in the upper end of the cylinder, a small imperforate cone supported in the lower end of the cylinder, and a conical ring supported between the two cones at the center of the cylinder; substantially as specified.

In testimony whereof I have signed my name to this specification in presence of two subscribing witnesses.

FREDRICH J. KOBUSCH.
